ART OF TIPPING LACES

Karl H. Andren, Milwaukee, Wis., assignor to
 Artos Engineering Company, Milwaukee, Wis.,
 a corporation of Wisconsin

Application March 3, 1939, Serial No. 259,618

9 Claims.

(Cl. 18—1)

The present invention relates to improvements in the art of applying tips to shoe laces or the like, and relates more specifically to improvements in the construction and operation of mechanism for applying so-called fiber or Celluloid tips to cords or laces.

Generally defined, an object of my present invention is to provide a new and useful method of insuring effective application of tips formed of relatively soft and pliable material to shoe laces or the like, at relatively high speed and with minimum difficulty and waste.

In the earlier days of the shoe lace manufacturing industry, it was common commercial practice to apply metal tips to the laces by wrapping a strip of thin metal about the medial portion of a piece of lace stock with the aid of cooperating forming dies, and by subsequently severing the enwrapping metal centrally so as to produce two complete tips one of which was permanently applied to each of the adjacent ends of the severed lacing. Machines of the type adapted to apply the metal tips in this manner are shown in Swift Patent No. 866,314, in Church Patent No. 895,724, and in Armitage Patent No. 1,423,894, and these machines operated quite satisfactorily when applying metal tips. During recent years it has been found more desirable to apply so-called "fiber" instead of metal tips, these fiber tips being formed of thin strips of Celluloid which, however, must be softened with the aid of suitable solvent and must also be subjected to heat, in order to permit free wrapping of the tipping material about the laces and to cause the wrapping sheet to retain its final tubular shape. With the advent of these fiber or Celluloid tips, many conditions have arisen to make lace tipping a delicate and difficult operation with the prior standard machines. It has been found that even after the forming dies have been properly set, and for various reasons, the tips frequently become distorted or misformed, and sometimes open up as they leave the dies, and in some cases the tipping stock does not overlap sufficiently, or the sheet material buckles. These detrimental actions take place because the Celluloid is relatively resilient and is made soft and pliable by the solvent and heat, and if the difficulty is not quickly discovered and corrected while the tipping machine is operating, considerable damage may result and much stock will be wasted. While these difficulties are not so pronounced and serious in slow hand operated machines, they become vital in the operation of high speed lace tipping equipment

and preclude the production of a succession of perfect lace tips.

I have discovered that correct curvature of the forming surfaces of the dies, is important in the production of perfect Celluloid tips, and if the die curvature and stock stops are not correct, the Celluloid strip will at times be improperly wrapped about the lace, thus resulting in defective tips. Then too, I have found that since the prior forming die assemblages have no means for controlling the action of the relatively moving tip forming dies, they do not function to uniformly compress the successive laces while the Celluloid strip is being wrapped therearound to the desired extent, so that uniform overlap is not obtainable with these prior structures. As a result of this omission, the forming slide of the die often starts too quickly and prevents the trailing end of the strip from being tucked in properly, or it does not start soon enough so that the leading edge of the strip will be wrapped around the tip and instead will be sheared off. In either case, imperfect tips are produced, and continued operation of the machine after one defective tip has been formed invariable results in the production of other subsequent faulty tips and precludes formation of uniformly perfect product at commercially satisfactory speeds.

It is therefore a more specific object of my present invention to provide instrumentalities whereby uniform and perfect successive tips may be produced automatically and at relatively high speed.

Another specific object of the invention is to provide an improved lace tipping die assemblage having properly curved and cooperating tip forming surfaces which will insure proper wrapping and tucking of the tip producing material.

A further specific object of the present invention is to provide improved means for controlling the movement of a pair of relatively movable tip forming dies so that uniform application of successive tips is assured at all times.

Still another specific object of my invention is to provide a method of applying perfect Celluloid tips to successive laces with the aid of automatically functioning dies and at high speed, with minimum attention and at relatively low cost.

These and other specific objects and advantages will be apparent from the following detailed description.

A clean conception of the several steps constituting my improved mode of applying tips to

laces, and of the construction and operation of a machine especially adapted to tip shoe laces, may be had by referring to the drawings accompanying and forming a part of this specification 5 wherein like reference characters designate the same or similar parts in the various views.

Fig. 1 is a longitudinal vertical section through one of my improved shoe lace tipping die assemblies, showing the same applied to a fragment 10 of the frame of a shoe lace tipping machine;

Fig. 2 is a side elevation of the die assemblage of Fig. 1 showing the relative location of the shaft which carries the lace conveying spiders;

Fig. 3 is a top view of the forming die assembly of Figs. 1 and 2;

Fig. 4 is an end view of the same die assembly;

Fig. 5 is a transverse vertical section through the lace tipping machine, taken along the line 20 5-5 of Fig. 1;

Fig. 6 is a similar transverse vertical section through the machine, taken along the line 6-6 of Fig. 1;

Fig. 7 is another transverse vertical section 25 through the die assemblage, taken along the line 7-7 of Fig. 1;

Fig. 8 is a perspective view of a shoe lace tipping machine having one of my improved die assemblages in operative position therein, and another such assemblage positioned upon the 30 frame thereof;

Fig. 9 is an enlarged diagrammatic section of my improved forming die assemblage showing the same in the initial position during application of a tip forming strip to a lace;

Fig. 10 is a similar view showing the movable die approaching the normally stationary die, and the tip stock severed from the supply source and initially confined between the dies;

Fig. 11 is another similar view showing the movable die advanced sufficiently to urge the tip stock against the other die and to initially bend the stock, and also showing the lace partly compressed;

Fig. 12 is an additional similar view showing the next step of the tip forming and applying process;

Fig. 13 is a similar view to a reduced scale, showing the position of the die assemblage while 50 the movable die is completing the inner end tuck and the other die is still in fixed position;

Fig. 14 is another enlarged similar view of the die assemblage showing the tip formation just prior to final completion;

Fig. 15 is a view similar to Fig. 14 showing the completion of a tip;

Fig. 16 is a more complete section similar to that of Fig. 1, but showing the forming dies moved to the position shown diagrammatically 60 in Fig. 9;

Fig. 17 is a view similar to that of Fig. 16 but showing the forming dies in the same position as in Fig. 14; and

Fig. 18 is another view similar to Figs. 16 and 65 17 but showing the dies in final tip forming position as in Fig. 15.

While I have shown and described my invention as being specifically embodied in a machine for automatically applying double length Celluloid tips to the adjacent interconnected ends of two laces simultaneously, and wherein the tip and lace stock are subsequently severed by relative movement of portions of the dies, it is not 70 my intention to thereby unnecessarily restrict the scope and adaptation of the improvement.

Referring specifically to Figs. 1 to 8 inclusive of the drawings, the standard shoe lace tipping machine shown therein comprises in general a main frame 20; a horizontal rotary shaft 21 journaled in the frame 20; a pair of laterally spaced 5 lace clamping spiders 22 mounted upon the medial portion of the shaft 21; a pair of lace conveying spiders 23 adjustably secured to the shaft 21 outwardly beyond the spiders 22; a reciprocable shuttle 24 slidable along the frame 20 and 10 adapted to supply a continuous strand of lacing stock 25 to the arms of the spiders 22, 23 during revolution of the latter; solvent applying means 26 coacting with the successive lace sections between the spiders 22 and above the shaft 21; a 15 forming die assemblage disposed upon the frame 20 laterally adjacent the mid-portion of the shaft 21 and between the spiders 22; and an actuating shaft 27 for the forming dies also journaled in the frame 20 and having thereon cams which are 20 housed within a casing 28. The solvent applying means 26 are carried by frame 20 and by a bracket 29 secured to the casing 28 and upon which a solvent supply reservoir 30 is also mounted, and the frame 20 is also provided with 25 an electrical control element 31 near the tipping zone, and with feed mechanism 32 for intermittently feeding a strip of Celluloid stock 33 into the zone of action of the forming dies during normal operation of the tipping assemblage. All 30 of these elements are of old and relatively well known construction as indicated by the prior patents hereinabove referred to, except that the die assemblage is of improved construction.

My present improved die assemblage which is 35 associated with the main frame 20 between the clamping spiders 22, comprises in general a base 34 having a central opening for permitting delivery of the Celluloid stock 33 upwardly therethrough; an elongated work support 35 and an 40 forming block 36 secured to a plate 37 which is mounted upon the base 34; a pair of relatively movable but normally stationary laterally adjoining forming dies 38, 38' resting upon said block 36 and plate 37; 45 and a pair of relatively displaceable and simultaneously movable laterally adjoining forming dies 39, 39' carried by slide members 40, 40' which are slidably mounted upon the base 34. The base 34 has one or more electric heating elements 41 50 therein which are cooperable with the control element 31; and also has a transverse end plate 42 rigidly attached thereto, this end plate 42 being provided with set screws 43 which are cooperable 55 with the adjacent end of the die supporting plate 37 in order to accurately initially position the work support 35 and the forming block 36 attached to the plate 37. The control element 31 is insulated to accurately gauge the heat of the 60 bottom of base 34, and cooperates with switch mechanism in a well known manner, and the entering Celluloid stock is protected against excessive heat by an insulating guide 44 the upper 65 end of which coacts with the end of the plate 37 near the work support 35. The opposite sides of the frame 34, are provided with special adjustable guides 45 for steadyng and eliminating vibration of the lace stock 25 as the successive sections are positioned upon the work support 35 by the revolving clamping and conveying spiders 22, and the upper edge portion of the forming block 36 adjacent the work support is provided with a chamfer 46 as clearly shown in Figs. 9 70 to 15 inclusive.

The cooperating faces of the forming dies 38, 38', 39, 39' are preferably accurately curved as illustrated in Figs. 9 to 15 inclusive and the normally stationary dies 38, 38' are provided with stops 41 which are cooperable with the overlapping portions 48 of the movable dies 39, 39' to prevent damaging of the sharp and delicate die edges when the machine is operating and no lace and tip stock is being supplied. The forming dies 38, 38' are secured to slides 49, 49' respectively, which are slidably confined in the base 34 and each of which has a lug 50 movable between limit stop screws 51, 52, but movement of the slides 49, 49' and dies 38, 38' away from the work support 35 is at all times restrained by compression springs 53 coacting with the slides 49, 49' through plungers 54 and reacting against the end plate 42 as indicated in Figs. 1, 13, 16, 17 and 18. Top wedges 55 which are interposed between the top of the base 34 and the slides 49, 49' are adjustable by means of set screws 56 to eliminate excessive play, and the outer ends of the plungers 54 are adapted to be engaged by the adjacent ends of the members 40 during the final tipping operations, as shown in Figs. 14, 15, 17 and 18.

The slide members 40 which carry the reciprocable forming dies 39, 39' are slidably confined in the base 34 by means of top wedges 57 which are adjustable with the aid of set screws 58, 30 and each member 40 has a driving block 59 adjustably attached to the lower portion thereof by means of screws 60 and locking set screws. The blocks 59 are adapted to be reciprocated in properly timed relation to each other, by means of reciprocable elements 61 specifically shown in Fig. 1, and these elements 61 are movable by suitable cams carried by the drive shaft 21 shown in Fig. 8, in a manner which will be subsequently described. It is to be noted, that by adjusting the relative positions of the blocks 59 and members 40 with the aid of the screws 60, the movable forming dies 39, 39' may be accurately positioned for proper cooperation with the normally stationary dies 38, 38', and it is essential that the 45 various parts cooperate with minimum necessary clearances so that the dies will always coat with each other properly. The complete forming die assemblage is obviously carried by the base 34 which may be removably attached to the main frame 20 in any suitable manner, and convenient insertion and removal of the die assemblage may be effected as indicated in Fig. 8, with the aid of eye-bolts 62. In actual commercial practice, a 50 spare die assemblage such as shown in Fig. 8, is preferably kept available so as to prevent excess waste of time in case replacement of a die unit becomes necessary, or for quick change of machine to a different size of die for a different lace.

60 During normal operation of my improved shoe lace tipping mechanism, and while carrying on my improved method of applying tips to the successive laces, the machine is being driven so as to cause the shuttle 24 to continuously wind lacing stock 25 about the arms of the intermittently revolving spiders 23 and through the clamps carried by the arms of the spiders 22. The die assemblage is being operated in unison with the revolving spiders 22, 23, so that successive stretches of lace stock are automatically urged past the guides 45 and are positioned by the clamping spiders 22 upon the work support 35. The successive steps which follow this positioning of a section of lace stock 25 upon the work support 75 70 35, are illustrated diagrammatically in Figs. 9

to 15 inclusive, and it will be understood that the feed mechanism 32 is functioning to intermittently advance the Celluloid tip stock 33 as the forming dies complete their operations. This stock 33 may be either in the form of a single 5 strip, or two laterally separated strips.

Referring specially to Fig. 9, the movable forming die 39 is advancing toward the stationary die 38 and the lower edge of the die 39 is cooperating with the adjacent upper edge of the work support 35 to shear off a piece of the Celluloid stock 33 sufficient to form a tip. The lower edge of the die 38 is in alignment with the chamfer 46, and is held in this position by the heavy spring 53 against stop means 51, and the lace stock 25 is 15 resting upon the work support 35 somewhat off center.

As the movable die 39 continues its forward movement to the position shown in Fig. 10, the portion 48 thereof overlaps the die 38 the position of which remains momentarily unchanged. The die 39 has carried the lace stock 25 some distance over the work support 35 and has carried the severed piece 33' of Celluloid stock into contact with the curved face of the stationary 25 die 38. The die 38 is, however, maintained in relatively fixed position by the spring 53.

In Fig. 11 I have shown the movable die 39 advanced still further toward the relatively fixed die 38. The lace stock 25 has been somewhat 30 compressed and bulged, and it will be understood that the portion of the lace stock 25 at the zone of application of the tip has been previously saturated with solvent by the means 26 which receive their supply of solvent from the reservoir 35 30. In the disclosure of Fig. 11 the section 33' of Celluloid stock has been somewhat further distorted and urged into contact with the upper part of the lace stock 25, and one edge of the stock piece 33' is being forced downwardly around 40 the curved face of the fixed die 38. The dies 38 and 39 are so curved in relation to each other that the bending of the Celluloid always takes place as shown.

As the movable die 39 advances to the position 45 illustrated in Fig. 12, it further compresses the solvent soaked lace stock 25 and forces the same into contact with the Celluloid piece 33' which has now been forced into snug conformity with the curvature of the fixed die 38 and with the 50 chamfer 46 in the forming block 36. The opposite edge of the Celluloid piece 33' is being forced downwardly along the curved face of the movable die 39.

In Fig. 13 the movable die 39 has advanced sufficiently to cause the edge of the Celluloid piece which was traveling downwardly along the curved face of the die 39, to be tucked about the solvent saturated section of the lace stock 25 and behind or within the edge of the piece 33' which coacts 60 55 with the chamfer 46. It is to be noted that the end of the member 40 up to this time has not yet engaged the adjacent end of the plunger 54.

In Fig. 14 the member 40 has advanced into contact with the plunger 54 and the movable die 65 39 has urged the Celluloid piece 33' into snug coaction with the curved faces of the dies 39, 38, and the downwardly directed end of the piece 33' is about to be lapped over the opposite inwardly tucked edge of this piece. 70

Subsequent advancement of the member 40 and die 39 carries the lace stock 25 away from the chamfer 46 and urges the plunger 54 rearwardly so as to remove the pressure from the heavy spring 53 and allow the compressed mass 75

of lace and Celluloid to urge the now unloaded slide 49 and the die 38 to follow the die 39 as one unit with a fixed space between the edges of same. This movement causes the outer edge 5 of the Celluloid piece 33' to be folded by the stationary folding block 36 into snug engagement with and over the inwardly tucked edge of the piece 33', thus completing the action of wrapping the Celluloid strip about the lace stock 25. This 10 action and cooperation of the dies also positively prevents the leading edge of the piece 33' from remaining in the notch 46 and being sheared off.

The mechanism is then automatically operable to cause one set of dies 38', 39' to be arrested by 15 the corresponding stop screw 52, while the complementary set of dies 38, 39 continues its forward movement against the corresponding screw 52, thereby shearing the piece of lace stock and the embracing tip, into two parts and providing 20 a completed tip at each of the adjacent ends of the severed stock 25. When the wrapping operation has been thus completed in a heated zone, there is a slight dwell and the solvent with which the lace stock 25 is saturated will then quickly 25 evaporate and cause the tip to set. The dies 38, 38', 39, 39' are subsequently returned to the position shown in Fig. 1, and the spiders 22, 23 are revolved sufficiently to carry another section of solvent soaked lace stock 25 into position upon 30 the work support 35. Simultaneously with this operation, the severed and tipped lace stock 25 is advanced by and drops from the spiders 22, 23, leaving the bared arms of these spiders free for the reception of subsequent lacing. In this manner, the successive laces are automatically tipped 35 and cut into proper length, and are delivered from the machine, and it has been found practical to operate machines of this type at extremely high speed sufficient to produce as high 40 as 140 laces per minute, without any failures.

From the foregoing detailed description, it will be apparent that my present invention provides extremely simple yet highly efficient apparatus for rapidly, accurately, and uniformly applying 45 tips to successive laces, without danger of failures. It will be apparent that the proper curvature of the forming dies is essential, and that the provision of the chamfer 46 in the forming block 36 is also important. But of primary importance 50 is the provision of the plunger 54 and spring 53 which permits the dies to relatively adjust themselves so as to insure uniformity in the wrapping operation and which eliminate shearing off of the leading edge of the tip stock. With my present 55 improvement, it has been found possible to uniformly tip the successive laces with minimum failures and at relatively high speed, and by virtue of the various adjustments provided, the mechanism can be readily set so as to insure 60 continued operation throughout long periods of time and with minimum attention. With my improved process, the completion of the tipping operation and the severing is effected after the lace stock has been removed from the work support 65 and the completion of each operation is actually effected by the forming block 36. The movable die besides serving to wrap the Celluloid about the laces, also functions as a cutter to remove successive sections of the Celluloid from 70 the supply strip and since each of the sections 33' is acted upon precisely the same manner by the accurately formed and specially curved forming dies, uniformity in application of the tips must necessarily result. The invention has proven 75 highly successful in actual commercial use, and

the structure for carrying on my improved process is obviously so simple that it can be manufactured and operated at extremely moderate cost.

It should be understood that it is not desired to limit this invention to the exact details of 5 construction or to the precise steps of the process, herein shown and described, for various modifications within the scope of the claims may occur to persons skilled in the art.

I claim:

1. The method of wrapping a piece of tip stock about a lace, which comprises, confining the piece of tip stock and the lace in a contracting space having curved opposite ends and an off-set notch adjacent one of the ends, contracting the space 15 to move one end of the piece into the notch and into snug coaction with the adjacent curved end and simultaneously initially distorting the lacing to partially conform with the interior surface of curved piece, tucking the edge of the piece remote 20 from the notch beneath the edge thereof confined within the notch, resiliently restraining the contracting action to which said space is subjected, and subsequently moving the lace and embracing piece of tip stock away from the notch under the 25 influence of said resilient restraining force to wrap the outer edge of the piece snugly over the tucked end thereof.

2. The method of applying a tip to a lace, which comprises, confining a lace and a piece of 30 tip stock in a space having relatively approachable curved end walls and an off-set notch contiguous with one of the walls, moving the walls toward each other while resiliently restraining the contracting action of the confining space to 35 initially compress the lace and to force one end of the stock into said notch, tucking the opposite end of the stock between the lace and the end portion confined in the notch, and thereafter moving the fixed confining space while still subjected to said restraining force away from the notch to wrap said end portion snugly against and over the tucked end.

3. The method of tipping laces, which comprises, wrapping a piece of tip stock about a solvent saturated lace and gradually compressing the enwrapped portion in a space one wall of 45 which is resiliently restrained by a pressure exceeding the compression force.

4. The method of tipping laces, which comprises, wrapping a piece of tip stock about a solvent saturated lace and gradually compressing the enwrapped portion in a space one wall of which is resiliently restrained by a pressure exceeding the compression force, and thereafter 55 severing the lace and wrapping stock to produce segregated independent finally tipped lace ends.

5. In combination, a work support, means forming an offset notch at one end of said support, a pair of relatively movable dies having co-operating curved surfaces one of which normally terminates at said notch, means for positioning lace stock and tip forming material between said dies, means for relatively moving said dies to wrap the tip forming material about the stock 65 and to cause said notch forming means to complete the wrapping operation while said dies are definitely spaced, and means for resiliently restraining the approaching movement of said dies during the wrapping operation.

6. In combination, a work support, means forming an off-set notch beyond one end of said support, a pair of dies relatively movable along said support and having curved approachable surfaces, means for positioning lace stock and a 75

piece of tip forming sheet material between said surfaces, means for moving said surfaces toward each other to initially wrap said material about said stock and to finally cause said notch forming means to complete the wrapping operation under controlled conditions, and means for resiliently restraining the approaching movement of said surfaces.

7. In combination, a work support, a forming block coacting with said support to provide a notch adjacent to the latter, a normally fixed die resiliently restrained against movement and having a curved forming face contiguous with said notch, a movable die having a curved face movable toward the curved face of said fixed die, said movable die having a cutting edge contiguous with its curved face and cooperable with said work support to sever sections of tip forming sheet material and to deliver the same between said curved faces, means for positioning lace stock between said curved faces, and means for initially moving said movable die toward said curved die and for subsequently moving said dies in fixed relation away from said notch over said forming block to wrap said tip forming sections about the lace stock.

8. In combination, a work support, a forming block coacting with said support to provide an

intervening off-set notch, a normally fixed die resiliently restrained against movement away from said notch and having a curved face contiguous with said notch, a movable die movable toward said normally fixed die and having a curved face facing the curved face of said fixed die, means for feeding lace stock and tip forming material between said faces, and means for relatively moving said dies to cause said faces to wrap said material about said stock and to cause said notch to complete the wrapping operation.

9. In combination, a work support, a forming block coacting with said support to provide an intervening off-set notch, a normally fixed die resiliently restrained against movement away from said notch and having a curved face contiguous with said notch, a movable die movable toward said normally fixed die and having a curved face facing the curved face of said fixed die, means for feeding lace stock and tip forming material between said faces, means for relatively moving said dies to cause said faces to wrap said material about said stock and to cause said notch to complete the wrapping operation, and means for subsequently relatively moving portions of said dies to sever the tip and stock.

KARL H. ANDREN.
